UNITED STATES PATENT OFFICE.

NATHANIEL SOUTHGATE SHALER, OF CAMBRIDGE, ASSIGNOR TO THEODORE
A. DODGE, TRUSTEE, OF BROOKLINE, MASSACHUSETTS.

FRICITION DEVICE FOR LOCOMOTIVES.

SPECIFICATION forming part of Letters Patent No. 313,959, dated March 17, 1885.

Application filed April 4, 1884. (No model.)

To all whom it may concern:

Be it known that I, NATHANIEL S. SHALER, of Cambridge, county of Middlesex, and State of Massachusetts, have invented an Improvement 5 in Friction Devices for Locomotives, of which the following description, in connection with the accompanying drawing, is a specification, like letters on the drawing representing like parts.

10 My invention relates to a device for increasing the friction or holding power between the driving-wheels of locomotives and the rails.

The usual method of applying sand discharged on the rail through pipes leading from 15 a sand-box on the locomotive is objectionable on account of the unequal distribution of the sand or gritty friction-producing material, which is frequently accumulated in considerable quantities, and thus tends to retard the 20 wheels without producing the best effect for increasing the friction. It is essential for the best effect that a thin layer of gritty or friction-producing material should be interposed between the wheels and rails, so that the particles of gritty material embed themselves in 25 both opposed metallic surfaces, thereby binding, as it were, the said surfaces together or increasing the frictional or holding power between them.

30 My invention has for its object to insure the distribution of the gritty or friction-producing material in a thin layer between the wheel and rail, and in order to secure such effect the particles of gritty material are applied to the opposite sides of a flexible band 35 or strip of paper or other material capable of holding them, the said strip being fed to the point of contact between the wheel and rail when it is necessary to increase the friction or 40 holding power between them.

The drawing shows in side elevation a portion of a locomotive provided with a friction-increasing device embodying this invention. The gritty or friction-producing material, 45 which may be flint or sand, but which is preferably a harder material—such as magnetic iron-ore, emery, or corundum—is cemented or otherwise applied to one or both surfaces of a flexible band or strip, *a*, which may be 50 of paper or other suitable flexible material, it serving as a basis or support for a thin even layer of such gritty material. The band *a* is

preferably rolled into a coil on a reel, *b*, which may be supported on the locomotive-body at any convenient point, and may be inclosed 55 in a suitable case, if necessary. A tube, *d*, may be employed to guide the band from the reel to the point where it is to be delivered on the track at the front of the wheel, and the axle of the reel will be provided with actuating 60 mechanism operated from the cab, the said mechanism being shown as consisting of belts *e e'*, operated by a pulley, *f*, provided with a suitable handle. The engineer or attendant is thus enabled to cause the strip *a* to 65 feed downward through the tube *d* until it reaches the track and is caught between the track and the wheel, when it will be drawn off in proportion as the wheel advances until the coil is wholly exhausted, or is severed by a 70 suitable device, or is broken by checking the movement of the reel. The strip may be weakened from point to point—as by a transverse line of perforations—to cause it to break more 75 readily when its feeding movement is checked by stopping the pulley *f*. When one coil of the band of frictional material is exhausted, another one may be substituted.

I claim—

1. In a friction device for locomotives, a 80 flexible strip or band provided with gritty or friction-producing material, combined with mechanism for feeding the same between the track and the treads of the wheels, substantially as described.

2. In a friction device for locomotives, a coiled flexible band provided with gritty or friction-producing material, combined with a guide-tube for the said band leading from the coil to the track near the contact-point of 85 the wheels, substantially as described.

3. The flexible band provided with gritty or friction-producing material, combined with a reel for the said band when coiled, and actuating mechanism for the said reel, to operate 95 substantially as described.

In testimony whereof I have signed my name to this specification in the presence of two subscribing witnesses.

NATHANIEL SOUTHGATE SHALER.
